UNITED STATES PATENT OFFICE.

ROBERT ZAHN, OF PLauen, GERMANY; ALFRED RIETZSCH ADMINISTRATOR OF SAID
ZAHN, DECEASED.

SHUTTLE EMBROIDERY-MACHINE.

1,119,561.

Specification of Letters Patent.

Patented Dec. 1, 1914.

Application filed October 2, 1911. Serial No. 652,311.

To all whom it may concern:

Be it known that I, ROBERT ZAHN, a subject of the King of Bavaria, residing at Plauen, Vogtland, in the Kingdom of 5 Saxony, Germany, have invented certain new and useful Improvements in Shuttle Embroidery-Machines, of which the following is a specification.

The present invention relates to shuttle 10 embroidery machines and represents a solution of an often, but hitherto unsuccessfully tried problem to utilize the well known and approved principle of the shuttles of the Wheeler & Wilson type for embroidery machines of the type specified and shown in 15 my various United States patents. The employment of such shuttles has, outside of the advantage of permitting simple driving means, also the advantage consisting in the 20 possibility of accommodating in such shuttles a much greater thread supply than the shuttles of the type of ordinary sewing machines would allow. In order to entirely utilize this advantage, which is of still 25 greater importance for the embroidery machines of the type specified and shown in my various United States patents, than for ordinary sewing machines or embroidery machines of other type, the adjacently ar- 30 ranged shuttles contrary to earlier well known arrangements, are in vertical position movably connected each with a circular guide rotatable in vertical plane, the circular guides being all positively driven from 35 a common driving shaft and the shuttles being arranged to be easily removable from their guides. By virtue of such construction, it is possible to place the shuttles as close to one another as necessary and to 40 render them available for machines having the hitherto used smallest needle pitch of about $\frac{1}{8}$ of an inch. Earlier well known experiments consisted in placing the plane of the take-up movements horizontally. 45 This, however, prevented from arranging the centers of rotation closer together than the outer diameter of the casing permits, and, therefore, was available only for a needle pitch about 2 $\frac{1}{2}$ times as large as the 50 one for which my construction can be used. Nor were in the earlier constructions, the shuttles removable, so that in order to supply the shuttles with thread, the machine had to be stopped. The adjustment of the 55 tension of the thread was rendered difficult

or almost impossible in consequence of which the embroidery work was not uniform.

My invention is illustrated in the accompanying drawing, in which similar reference letters denote corresponding parts and in which—

Figure 1 is a side view of a stationary casing with the circular guide for the shuttle therein; Fig. 1^a is a front elevation of a part of the embroidering machine 65 showing the arrangement of the shuttles relative to one another; Fig. 2 is a section on line 2—2 of Fig. 1; Fig. 3 is a plan view; Figs. 4 and 5 are sections at right 70 angles of the shuttle; Fig. 6 is a side view and Fig. 7 a plan of the shuttle and illustrate together with Figs. 8—10 the operation of the shuttle.

In the drawing, which forms a part of 75 this specification, 1 denotes a metal bracket adapted to extend throughout the length of the frame of the embroidery machine (not shown). Screwed to or otherwise fixed each by a base 2 to the said bracket and adapted 80 to lie in a long row close to one another are the shuttle guides 3, 4, 6 made in form of casings. The bearing proper for the rotary shuttle is composed of two sections, the lower section 4 which by means of screw 85 bolts 5 is permanently fixed to the back 3 of the shuttle casing and a temporarily fixed upper section 6. In order to enable the section 6 being readily removed to allow of the removal or exchange of a shuttle, the section 6 is provided with a flange 7 to which 90 conical pins 8 are fixed adapted to engage notches in the upper margin of the back 3 of the casing. A swinging arm 9 fulcrumed to the back 3 of the guide is adapted to engage the upper section 6 to hold the same in proper position. Instead of the arm 9 any other suitable means for securing the part 6 in position may be used.

Within a circular cavity 12' in the back 100 3 of the guide a suitable driving member 12 is arranged which conforming with the cavity is also of circular shape and which in the present embodiment of my invention is shown to consist of a ring. This ring 12 105 is toothed on its periphery and on its face directed toward the body of the shuttle is provided with pins 10 and 11. The part 12 is adapted to revolve within the cavity in the wall 3 of the casing and to receive its 110

rotary motion through one of a series of gear sections 13 adapted to be fixed on a common shaft 13' arranged above the bracket 1 from the main shaft of the machine (not shown). The common shaft 13' of the series of gears 13 when given an oscillating motion will cause the said gears to carry along with them the corresponding parts 12, which by means of their pins 10 and 11 will each intermittently engage the corresponding shuttles to oscillate the said shuttles according to the direction of rotation.

My new shuttles of the Wheeler & Wilson type are each made of sheet metal (steel). The same is pressed into the form of a shell 14 which on its circumference is formed with a nose 20 serving as a hook (Figs. 6-10) and a neck portion 36, the object of which will be hereinafter fully specified. A cover 15 is hinged at 16 to the shell 14, to be capable of being tilted into open position 15' as indicated by dotted lines in Fig. 5. From the center of the vaulted bottom of the bowl or shell 14, a pin 17 rigidly secured thereto projects toward the cover and is slit almost throughout its entire length (Fig. 4) to allow of its being expanded so as to hold the bobbin 18 placed thereon from turning. The bobbin 18 is wound around a small paper tube 19 and is made thicker in the center than around the ends. The free end 24 of the cover 15 when closed catches in a groove 25 (Fig. 5) in the upper margin of the shell 14 to lock the same in position. The cover, as the shell 14, is pressed of sheet steel so as to form a circular depression 28 and a circular shoulder 27 around said depression.

In linear extension of the pin 17 and concentric with the center of the bobbin the cover 15 has a passage or hole 26 for the thread, which hole is in the center of the depressed surface 28 of the cover 15. The center of the bobbin which coincides with the center of the hole 26 is eccentric relative to the center 29 (Fig. 1) of the member 12. There are at certain points two other thread openings 30, 31 in the shoulder 27. Fas- tened at one end, as at 33, to the depressed surface 28 is a brake spring 32 made of thin steel plate (Fig. 8). The other end of said spring overlaps the thread portion located between 26 and 30. The pressure of the spring on the thread may be regulated by the means of an adjustable short finger 34 or the like fulcrumed to a pin 34'. It is not necessary to form the shoulder 27 all around the depression in form of a closed ring. It suffices when parts of it are at the points where in Figs. 6 to 10 the thread 18 or the thread loop 23' passes over the shoulder.

35 denotes the stitch plate, Figs. 1-3 and 6-10. The embroidery surface is denoted 65 by a dotted line X-X (Figs. 6-10).

The mode of operation is as follows: After the needle 21 has pierced the fabric X-X and entered through the hole in the stitch plate 35 at the side of the path of the oscillating shuttle, the needle thread loop 23' at the back of the fabric is formed (Figs. 6-7). As the needle begins its return movement and while the shuttle oscillates in the direction of the arrow in Fig. 8, its hook point 20 is caused to slip through the loop 23', so that the latter engages around the neck 36 and while the shuttle continues its rotation, the loop is expanded (Fig. 8). The needle 21 in the meantime has been withdrawn from the fabric. The shuttle thread 18 is conveyed from the bobbin through the passage 26, is then passed outward under the brake spring 32 through the openings 30, 31 made in the shoulder 27. The shuttle thread 18 is now carried through the expanded loop 23', whereupon the needle thread 23 is drawn taut by well known means (not shown) and the loop 23' slipping off the shuttle is tightened, which completes the stitch (Fig. 9). The shuttle then rapidly swings back into its initial position (Fig. 10). Owing to the eccentrical position of the passage 26 relative to the center of rotation of the shuttle, so much shuttle thread will be drawn out from the shuttle during the return stroke of the latter as became necessary by the previous displacement of the embroidery frame.

For the undisturbed formation of a stitch and loop, it is very important that no protruding parts of the cover as 33, 34 that overlap the threads 18 and 23' catch or damage the latter. For this purpose, the shoulder 27 is provided. Apart from that, the shoulder 27 serves another purpose, to wit, to prevent the thread 18 which owing to its natural elasticity has the tendency to curl, from winding around the needle point 21, which would result in the breaking of the needle. Of great importance for a uniform 110 unwinding of the thread 18 is also the feature, that the thread passage or hole 26 coincides with the center of the bobbin, so that the thread unwinding from the latter always finds unchanged resistances.

What I claim and desire to secure by Letters Patent is:

1. In an embroidering machine, a plurality of vertically oscillating shuttles arranged in a row extending longitudinally of the machine and adjacent to one another, a corresponding number of independent casings, one for each shuttle, and each casing having a removable section, a shuttle driving member in each casing and a common means for operating said shuttle driving members.

2. In an embroidering machine, a plurality of vertically oscillating shuttles, arranged in a row extending longitudinally of

the machine and adjacent to one another, a corresponding number of independent casings, one for each shuttle and each casing having a removable section, a shuttle driving member in each casing, a driven member, one for each driving member and a common means for operating said driven members.

3. In an embroidering machine, a plurality of vertically oscillating shuttles arranged adjacent to one another longitudinally of the machine, a corresponding number of stationary sectional casings forming raceways, one for each shuttle, one section of each of said casings being removable, a 15 driven toothed member in each of said casings adapted to transmit motion to the shuttle in said casing, a common longitudinal oscillatory shaft and toothed members on said shaft engaging with the corresponding 20 toothed members in the casing to oscillate the same and the shuttles.

In testimony whereof I affix my signature in presence of two witnesses.

ROBERT ZAHN.
